UNITED STATES PATENT OFFICE.

DAVID THORPE LEE, OF MAIDENHEAD, ENGLAND.

BOOT OR SHOE STRETCHER.

SPECIFICATION forming part of Letters Patent No. 448,352, dated March 17, 1891.

Application filed October 20, 1890. Serial No. 368,679. (No model.)

To all whom it may concern:

Be it known that I, DAVID THORPE LEE, a subject of the Queen of Great Britain, residing at Maidenhead, in the county of Berkshire, England, have invented a certain new and useful Improvement in Boot or Shoe Stretcher Trees, of which the following is a specification.

The object of this invention is to construct a cheap and efficient boot or shoe tree and stretcher designed more especially for stretching or keeping in shape the vamp or front of a shoe or boot and for providing a suitable handle for holding during the blacking or dressing of such shoe or boot.

In the accompanying drawings, Figure 1 is a side elevation, and Fig. 2 a plan, of the improved stretcher-tree.

It comprises the two corresponding stretching-halves A A, which are connected together at their rear ends by the removable screw-threaded pin B, and are likewise connected at or near the middle by the spiral spring C, of considerable strength. The gap between the parts A A may be filled toward the front with the filling-piece G, of the same external shape. The pin B serves also as a pivot for the lever H, which latter is provided with an indefinite number of holes H⁴, so that the pin 30 may be passed through whichever hole is most convenient for setting the tree to suit the particular shoe, &c., to be stretched. The lever H is shaped, as shown, with the heel projection H', the handle H², and preferably, also, 35 with the sole or lifting projection H³. The shape of the outline of the lever intermediate of these parts is immaterial, providing the

parts H' and H² particularly are located to act as described herein.

The handle H² being bent over toward the heel, the stretchers A A are pushed into the toe of the shoe or boot and the tree thrust well down into the shoe or boot, and the handle H² is pressed forward, whereby the part H' presses within the heel, driving the stretchers 45 forward into the toe and also raising the stretchers against the instep by the direction of the pressure on the pivot B, owing to the relative positions now occupied by the parts. The beveled shape of the lever H thrusts the 50 stretchers A A apart when so inserted and fixed in place. A reverse movement of the handle H² toward the heel displaces the heel-piece H'. The heel-piece having been thus displaced or drawn in, the stretcher may be 55 removed. J are holes for receiving corn-knobs in the known manner.

The improved stretchers may be made of wood or any suitable material.

I claim—

In a boot or shoe stretcher tree, the combination of the two parts A A with the expanding-spring C, forming a toe-stretching piece, and the lever H, pivoted on the rear end thereof, said lever having the handle H² and 65 the heel projection H' relatively located for action, substantially as set forth.

It witness whereof I have signed this specification in presence of two witnesses.

DAVID THORPE LEE.
